UNITED STATES PATENT OFFICE.

CHARLES S. DOLLEY, JOHN G. REHFUSS, AND JAMES HUNT, OF PHILADELPHIA, PENNSYLVANIA, ASSIGNORS TO THE UNIVERSAL FOOD AND LIQUID IMPROVING COMPANY, OF SAME PLACE.

BOTTLE-FILLING MACHINE.

SPECIFICATION forming part of Letters Patent No. 594,781, dated November 30, 1897.

Application filed April 3, 1897. Serial No. 630,612. (No model.)

To all whom it may concern:

Be it known that we, CHARLES S. DOLLEY, JOHN G. REHFUSS, and JAMES HUNT, citizens of the United States, residing at Philadelphia, 5 in the county of Philadelphia and State of Pennsylvania, have invented certain new and useful Improvements in Bottle-Filling Machines; and we do declare the following to be a full, clear, and exact description of the invention, such as will enable others skilled in the art to which it appertains to make and use the same, reference being had to the accompanying drawings, and to the letters of reference marked thereon, which form a part of this 15 specification.

This invention relates to certain new and useful improvements in apparatus for bottling liquids, and it is especially adapted for use in connection with that class of fillers 20 which are adapted to be operated by what is known as the "vacuum process."

The invention has for its object the general improvement upon the construction and to render more effective the operation of bottling machinery of this character.

The invention has for its more immediate object the provision of a simple, positively-operated, and inexpensive machine in which provision is had for the filling of bottles of 30 varying heights and in the provision of apparatus connected with a vacuum-chamber and source of liquid-supply whereby the movement of a single lever will effect the exhaustion of the air from the bottle to be filled 35 and the filling of the bottle.

A further essential object of the invention resides in the provision, in connection with the machine, of an expansion cylinder or chamber adapted to receive the surplus gas 40 contained within the bottle, thereby permitting the bottle to be completely filled.

To these ends and to such others as the invention may pertain the same consists in the novel construction and in the peculiar arrangement, combination, and adaptation of parts, all as more fully hereinafter described, shown in the accompanying drawings, and then specifically defined in the appended claims.

50 The invention is clearly illustrated in the

accompanying drawings, which, with the letters of reference marked thereon, form a part of this specification, like letters indicating the same parts throughout the several views, and in which drawings—

55

Figure 1 is a side elevation of a bottling-machine embodying our invention. Fig. 2 is a front view, upon an enlarged scale, of the upper portion of the machine, partly in section, the section being taken upon line 2 2 of 60 Fig. 3. Fig. 3 is an enlarged side elevation of the upper portion of the device, showing the vacuum and filling or supply ports. Fig. 4 is a transverse section upon line 4 4 of Fig. 2. Fig. 5 is a section upon the line 5 5 of 65 Fig. 4. Fig. 6 is a side view of the lower portion of the machine, the same being the reverse side of that shown in Fig. 1. Fig. 7 is an enlarged detail of the spring-controlled adjusting mechanism which compensates for 70 the difference in the heights of bottles to be corked. Fig. 8 is a perspective view, upon an enlarged scale, of the lower end of the plunger.

Reference now being had to the details of 75 the drawings by letter, A designates a standard, which in the present instance is shown cylindrical in form and secured to a suitable base B. At its upper end the said standard A is provided with an arm A², extending upward and slightly outward from the standard, and pivoted to the upper end of said arm is one end of an arm A³, which arm A³ at its opposite end is pivotally connected to a link A⁴, which link at its lower end is pivotally connected to the upper end of the plunger C.

D is a pedal pivoted within ears D' at the lower end of the standard, and the said pedal-arm D is connected with the lever A³ by means of a rod D², which extends upward through the 80 interior of the standard and is pivotally connected at the center of the arm A³, as shown at D'. In order to automatically hold the pedal normally in a raised position, as shown in Fig. 1, a spiral spring D⁴ is provided, which 90 spring encircles the upper portion of the rod D² and has bearings provided at its ends, as shown.

E is a bracket-shelf which is carried by a plate E², which plate is vertically movable 100

within suitable guides E³ upon the front face of the standard A. This shelf E is adapted to receive the bottle to be filled and is accordingly provided with a depression within 5 which the bottle to be filled is placed.

In order to effect an upward or downward movement of the shelf E, the following mechanism is provided.

F is a segmental gear pivoted at F' within 10 ears provided upon the standard A.

F² is a cam pivoted between arms F³ upon the front side of the standard A, and keyed to or integral with the said cam is a pinion F⁴, which is adapted to mesh with the teeth 15 of the segmental gear F.

G is a link pivotally connected at its upper end with the plate E² by means of a pin e², passed through a vertical slot e³, provided in 20 said plate. The lower end of the link G is provided with an opening within which is seated the pintle G' of the member G², the pintle G' being provided with laterally-extending lugs g, which are contained within 25 an elongated opening G³. At the upper end of the pintle G' a spiral spring G⁴ is provided, the tension of which spring serves to normally hold the member G² downward at the extreme limit of its throw. Pivoted within 30 the bifurcations G⁵ at the lower end of the member G² is a friction-roller G⁶, which bears upon the periphery of the cam F².

H is a casting provided at one of its sides with a cut-away portion H' to receive the cork. The lower portion H³ of the said casting H is 35 provided with a rubber cushion Y, which is adapted to inclose the upper end of the bottle, when by a downward pressure of the pedal the shelf with the bottle thereon is forced upward.

I is a casting or head-block within which are provided the vacuum and supply ports and the connections between the same and the ports leading to the bottle.

J^X is a hermetically-sealed expansion-cylinder from which in the operation of the machine the air may be exhausted for a purpose which will hereinafter appear.

J is a pipe leading to the vacuum-chamber, and J' a pipe leading to the source of supply. 50 Upon reference to Fig. 3 it will be seen that the said vacuum and filling pipes J and J' respectively enter the head-block I and that both of the said ports communicate directly with a common chamber K², which has direct 55 connection with the port leading to the bottle to be filled. In order to provide for the controlling of the inlets or ports leading from the vacuum and from the source of liquid-supply at will, we provide a shaft K, which is 60 provided with a valve K³, the said valve being normally seated by means of a spiral spring K⁴, surrounding the valve-stem within the chamber K², and the said valve is adapted to be opened against the tension of the said 65 spring by pressure applied to the extreme end or point K⁵ of the shaft. It will be observed that both the vacuum and the liquid-

supply ports are alike, and each being controlled by a spring-actuated stem K, carrying a valve controlling the port which communicates with the common chamber K², the two valve-stems K being upon the same horizontal plane and separated a short distance. 70

L is an operating-handle which is pivoted at its end L² between the projecting ends of the valve-stems K and is provided at its pivoted end with laterally-extending arms L³, which arms are adapted to contact with the valve-stems K, controlling the vacuum and liquid-supply ports upon moving the lever 80 from one side to the other, so as to exhaust the air from the bottle or cause the liquid to enter the same, as desired.

M is a small passage or port connecting the common chamber K² with the expansion-cylinder J^X, within which chamber K² is seated a plunger J², as shown. In order to stop the downward movement of the plunger C at the proper point to permit the surplus gas to leave the bottle before the cork is seated, as will 85 hereinafter appear, an angle-lever N, one arm of which is provided with an operating-handle N², is pivoted at its angle between ears N³, provided for the purpose upon the end of the head-block H. 90

The operation of the machine is as follows: The bottle to be filled is placed upon the vertically-movable shelf E. The pedal D is depressed and the shelf is raised by the rod G, the friction-wheel G⁶ at the lower end of said 100 rod traveling upon the cam F² and the said cam being rotated by the engagement of the pinion F² with the segmental gear F. Simultaneously with the upward movement of the shelf the plunger C is forced downward 105 through the connections, consisting of the rod D⁴, lever A³, and link A⁴, existing between the pedal and plunger. The plunger in its downward movement forces the cork, which has previously been placed in the opening H², downward within the casting H, the 110 said downward movement of the plunger being stopped by the arm N of the angle-lever N², the operating-arm of which has been thrown upward, so as to throw the arm N 115 against the plunger-rod C, where it is brought in contact with the link A⁴. The cork when forced downward to this point closes the opening in the upper end of the casting H; but a slight space intervenes between the 120 bottle-neck and the chamber K². By throwing the operating-lever to the right the arm L³ is brought into contact with the valve-stem K, controlling the vacuum-port, and the air is at once withdrawn from the bottle. 125 The operator then throws the lever L to the left, thus opening the port leading to the source of liquid-supply, and the bottle is filled. The expulsion of the gas from the charged liquid during the filling process 130 causes the gas to pass through the port M into the hermetically-sealed cylinder J^X, where it drives the piston in said cylinder upward, thereby relieving the pressure within

the bottle sufficiently to permit the bottle to be filled, as will be readily understood from the foregoing description, and as the gas enters the said cylinder J² the piston contained therein is forced upward. The bottle having been thus completely filled, the lever N² is forced downward, thus throwing the arm N away from the plunger-rod and permitting the plunger to be forced downward. A slight movement upon the pedal will then suffice to seat the cork within the bottle. The cork is then clamped or secured in place. A slight upward movement upon the pedal at this point will cause the plunger to slightly rise from the cork, thus permitting the removal of the bottle from the machine, a further upward movement restoring the parts to their original positions.

Having thus described our invention, what we claim to be new, and desire to secure by Letters Patent, is—

1. In a bottle-filling machine, an upright, a treadle pivoted thereon, a toothed segment also pivoted upon the standard and connected to the treadle, a pinion with which the segment engages, and a cam, the pinion and the cam being connected so as to rotate together; combined with a pivoted arm, and a rod for moving the bottle-support vertically, substantially as shown.

2. In a bottle-filling machine, an upright, a treadle pivoted thereon, a toothed segment also pivoted upon the standard and connected to the treadle, a pinion with which the segment engages, a cam secured to the pinion so as to revolve therewith, and a rod for moving the bottle-support vertically, combined with a spring-actuated rod connected to the treadle, a pivoted lever A³, and a plunger pivoted to the free end of the lever A³ for driving the cork at the same time that the bottle is forced upwardly, substantially as described.

3. A vertically-moving bottle-support pro-

vided with a vertical slot, the rod G having its upper end loosely fastened in the slot of 45 the bottle-support and which rod has a recess formed in its lower end and lateral openings through its sides, combined with the member G² provided with the thimble G', provided with lateral lugs g which extend outwardly 50 through the lateral openings in the rod, a spring placed in the rod, and a mechanism for moving the rod vertically, substantially as set forth.

4. In a bottle-filling machine, a treadle-operating mechanism, an operating-rod connected thereto, the lever A³ pivoted to the top of the upright or frame, a spring placed upon the rod, the link A⁴ and the plunger C, combined with a pivoted lever N which is adapted 60 to be moved into contact with the plunger, substantially as specified.

5. In a bottle-filling machine of the character described, the combination with the cork-seating plunger, of a pivoted lever, adapted 65 to limit the downward movement of said plunger, substantially as described and for the purpose specified.

6. The combination with the upright A, the vertically - movable bottle-support, the segment-gear F, the cam F², the pinion F⁴ upon the cam-shaft, and a link connecting the segment-gear with the pedal, the rod G carrying at its lower end a friction-wheel, adapted to travel upon the periphery of the cam, substantially as described and for the purpose specified.

In testimony whereof we affix our signatures in presence of two witnesses.
